James M. Duffie
Inventor.

United States Patent Office.

JAMES McDUFFIE, OF HELLER'S CORNERS, INDIANA.

Letters Patent No. 69,354, dated October 1, 1867.

IMPROVEMENT IN WAGON-SPRING.

The Schedule referred to in these Letters Patent and making part of the same.

TO ALL WHOM IT MAY CONCERN:

Be it known that I, JAMES McDUFFIE, of Heller's Corners, in the county of Allen, and State of Indiana, have invented certain new and useful Improvements in Wagon-Springs; and I do hereby declare that the following is a full, clear, and exact description thereof, reference being had to the accompanying drawings, and to the letters of reference marked thereon, in which—

Figure 1 represents a vertical section.

Figure 2 represents a detached view.

Figure 3 represents a detached view.

The nature of my invention consists in an improved method of constructing wagon and cart-springs, which may be readily attached to or detached from the wagon, as desired by the operator.

To enable others skilled in the arts to make and use my invention, I will proceed to describe its construction and operation.

A represents the spring, which is constructed, as seen in figs. 1 and 2, of a bar of steel or other metal, which is provided with suitable loops, *a*, at each end, as seen in fig. 1, equidistant from the centre and loop. On each side I form loops *b*, which are secured to the under surface of the spring. These loops rest upon the bolster of the wagon (see fig. 1) and support the wagon-box or bed. B B are gibbs and keys which are constructed as seen in the drawings, or in any other desirable manner. They pass through the end loops *b b*, and serve to give to the spring, when in use, a sufficient degree of tension, as will be readily understood. Any other method of applying said tension may be used equally as well, and would be equivalent to the gibbs and keys. C represents the spring-bar or supporter, which is formed, as seen in the drawings, figs. 1 and 3, of a flat wooden bar of a suitable length, breadth, and thickness, having a slot the width of the spring formed through it, as seen at D. This slot is in its centre cut entirely through, while at or near its ends there is a portion of the wood left which is carved out, as seen in the drawings at *f*, leaving a projection which serves as a support, and acts in combination with the spring and its supporters *b b*. Just outside of these projections *f* I form mortises *g g*, which are cut transversely through the bar, for the purpose of receiving the gibbs or keys. These mortises are positioned so as to come in range with the loops on the ends of the spring through which the gibbs and keys pass.

Having thus fully described the construction of the apparatus, I will now proceed to describe its operation, which is as follows: The bar or spring-supporter, with the spring properly adjusted, is placed on each of the bolsters, in the position seen in fig. 1, and the wagon-box or bed is then adjusted to its proper position, and the apparatus is ready for use. The loops on the under side of the spring elevate the spring, and the strong tension given by the gibbs and keys renders it very elastic, so much so that while it will support a heavy load and operate well, it will operate equally well when the wagon is not loaded. When desirable to use the wagon without the spring or bar, they may be readily removed. This arrangement is applicable, as well to carts, drays, and other vehicles, as to wagons.

The advantages of this apparatus are, first, that it is cheap, effective, and durable, and takes the place of springs of all other forms for the purpose of heavy-draught wagons, carts, or other vehicles. The jar and concussion may be effectually prevented by the use of this spring on wagons where the use of any other form of spring is entirely impracticable. The ease and facility with which this spring may be removed or replaced on wagons particularly recommends it to the practical operator. This apparatus may be attached to the bed of the wagon, or to the common bolster, or may be separated from either.

What I claim as new, and desire to secure by Letters Patent, is—

The spring A, in combination with the gibbs and keys B, and the bar C, said springs and bar being constructed in the manner and for the purposes herein described and set forth.

JAMES McDUFFIE. [L. S.]
